UNITED STATES PATENT OFFICE.

CHARLES H. SHEPARD, OF BROOKLYN, NEW YORK, ASSIGNOR TO WYCKOFF, SEAMANS & BENEDICT, OF ILION, NEW YORK, A CORPORATION OF NEW YORK.

TYPE-WRITING MACHINE.

SPECIFICATION forming part of Letters Patent No. 700,445, dated May 20, 1902.

Application filed March 8, 1901. Serial No. 50,306. (No model.)

To all whom it may concern:

Be it known that I, CHARLES H. SHEPARD, a citizen of the United States, and a resident of the borough of Brooklyn, city of New York, in the county of Kings and State of New York, have invented certain new and useful Improvements in Type-Writing Machines, of which the following is a specification.

This invention relates to ink-ribbon spools, such as used in type-writing machines.

The object of the invention is to provide improved means for attaching the ribbon to the spool.

The invention consists in certain combinations of devices and features of construction, all as will be fully hereinafter set forth, and particularly pointed out in the concluding claims.

In the accompanying drawings, Figure 1 is an edge view of a spool provided with my improvement, the ribbon-clasp being slightly raised, so as to disclose the needle-points upon which the ribbon is impaled. Fig. 2 is a cross-section of the spool, showing the ribbon-clasp swung away from the core and one end of a ribbon placed over the latter. Fig. 3 is an edge view of the devices shown at Fig. 4. Fig. 4 is a side view, a portion of the head of the spool being broken away. Fig. 5 is a perspective view of a clasp detached from the spool. Fig. 6 is a cross-section of a spool, showing a modified construction of clasp.

In the several views similar parts are designated by similar characters of reference.

The head or front flange of the spool is designated as 1, the rear flange as 2, and the wooden core as 3. Between the flanges is swung upon pivots 4 a clasp consisting of opposite arms 5, a cross-piece 6, and an extended finger 7, which normally curves closely around the core of the spool and engages by its tip a flattened or recessed part 8, formed upon the periphery thereof about diametrically opposite from the hinge 4, so as to lock the clasp in working position. The cross-piece 6 of the clasp or bail is provided with a portion 9, which extends longitudinally thereof and is bent at an angle thereto, so as to form a ledge, which is provided with a row

of perforations or notches 10. In the periphery of the core is cut a longitudinal recess 11, adapted to the clasp and having an abrupt face 12, against which the ledge 9 bears. Projecting from the face 12 is a row of impaling points or needles 13, opposite the notches 10 in the clasp.

The end of the ribbon is placed upon the core so as to cover the recess 11, as illustrated at Fig. 2. Then the clasp is swung to its seat upon the core by means of a finger piece or pin 14, which is formed upon one of the arms 5 and extends through an arc-shaped perforation 15, formed in one head of the spool, so as to be convenient to the operator. The ledge 9 upon contacting with the ribbon 16 A doubles the latter into the recess 11 and impales it upon the needles 13. Preferably the ribbon is also firmly clamped between the ledge and the opposing face 12 of the recess 11, as illustrated at Fig. 4. The finger 17 springs outwardly when slipping over the edge of the recess 8 and then snaps into said recess, (see Fig. 4,) thereby securely retaining the clasp in working position and preventing accidental detachment of the ribbon. In order to detach the ribbon, it is only necessary to press the handle 14 outwardly, whereby the clasp is swung to the Fig. 2 position, thereby releasing the ribbon, which may be withdrawn from the impaling-needles.

It will be seen that the arms 5 are thin and lie flat against the inner sides of the spool-flanges and that the cross-bar 6, as well as the finger 7, which forms a continuation thereof, are also thin and hug closely the periphery 18 of the spool-core, so as to leave practically the same amount of space for the ribbon as if no clasp were present.

Preferably the arms 5, cross-piece 6, ledge 9, and finger 7 are stamped from a single 190 piece of sheet metal. Thus it will be seen that by the employment of an inexpensively-manufactured device the ribbon may be readily attached to the spool or detached therefrom, as desired, without risk of soiling the 195 fingers.

Referring now to Fig. 6, it will be seen that the needles 13 are omitted. One or more

teeth 16 are formed upon the cross-piece 9^a of the clasp or bail, and a longitudinal recess or undercut 17 is formed at the lower part of the abrupt face or abutment 12^a. When a 5 ribbon is to be attached, the clasp is swung to the Fig. 2 position and the ribbon placed over the recess 11. Then the clasp is swung back to the Fig. 6 position, the ribbon being doubled into the undercut 17 by the teeth 16, 10 which also indent or impale the ribbon, so that the latter becomes firmly attached to the spool.

What I claim as new, and desire to secure by Letters Patent, is—

15 1. In a ribbon-spool, the combination with a pair of flanges and a core, of a bail arranged between the spool-flanges and pivoted thereto, said bail having a cross-blade or ledge 9 provided with notches or openings, a recess 20 in the core having an abrupt face opposed to said ledge, and impaling-needles projecting from said abrupt face opposite said notches or openings.

2. In a ribbon-spool, the combination with a 25 pair of flanges and a core, of a clasp consisting of opposite arms 5 which are pivoted at their outer ends to the flanges, a cross-piece 6, and an extended finger 7 which curves around the core of the spool and is adapted 30 to retain the clasp in working position.

3. In a ribbon-spool, the combination with a pair of flanges and a core, of a clasp consisting of opposite arms 5, which are pivoted at their outer ends to the flanges, a cross-piece 35 6, and an extended finger 7 which curves around the core of the spool and is adapted to retain the clasp in working position, said core having a recessed portion 8 formed in its periphery for engaging the tip of said finger.

40 4. In a ribbon-spool, the combination of a pair of flanges, a core, a bail comprising a cross-piece and arms 5 whose outer ends are pivoted to the flanges, a series of openings in said cross-piece, and a series of impaling- 45 points fixed in the core opposite said openings.

5. In a ribbon-spool, the combination with a pair of flanges and a core, of a clasp arranged 50 between the flanges and comprising a cross-piece and arms whose outer ends are pivoted to the flanges, said cross-piece having a portion 9 which is bent at an angle to the cross-piece so as to form a ledge, a row of notches or openings 10 formed in said ledge, a longitudinal recess formed in the spool-core, and 55 a series of impaling-points fixed in said recess opposite said notches or openings.

6. In a ribbon-spool, the combination with a pair of flanges and a core, of a longitudinal 60 recess formed in the core and having an abrupt face, and a clasp pivoted upon the spool-flanges and having a part which enters said

recess and coöperates with said abrupt face to clamp the ribbon.

7. In a ribbon-spool, the combination with a 65 pair of flanges and a core, of a ribbon-clasp comprising arms 5, cross-piece 6, ledge 9, and locking-finger 7, all formed from a single piece of sheet metal, and means upon the core for coöperating with said clasp to hold the 70 ribbon.

8. In a ribbon-spool, the combination with a pair of flanges and a core, of a ribbon-clasp comprising arms 5, cross-piece 6, ledge 9 and locking-finger 7, all formed from a single 75 piece of sheet metal, and means upon the core for coöperating with said clasp to hold the ribbon, one of said arms 5 having a finger-piece 14 which projects through an opening 15 in the contiguous spool-flange. 80

9. In a ribbon-spool, the combination with a pair of flanges and a core, of a bail-like clasp whose opposite arms are pivoted at their outer ends to the inner sides of the flanges, means upon the core for coöperating with said clasp 85 to hold the ribbon, and a finger-piece upon one of the bail-arms which projects through a slot formed in the contiguous spool-flange.

10. In a ribbon-spool, the combination of a core having a recess, an impaling-pin projecting into said recess, and a device for carrying the end of the ribbon into said recess and impaling it upon said pin. 90

11. In a ribbon-spool, the combination of a core having a recess, an impaling-pin projecting thereinto, and a swinging bail-like clasp adapted to carry the ribbon into said recess and force it upon said pin. 95

12. In a ribbon-spool, the combination of a core having a recess, a swinging clasp adapted 100 to carry the end of the ribbon into said recess, and an impaling point or points for holding the ribbon in said recess.

13. In a ribbon-spool, the combination of a core having a recess, a swinging clasp adapted 105 to carry the ribbon thereinto, an impaling point or points adapted to hold the ribbon in said recess, and means for holding the carrying portion of said clasp within said recess.

14. In a ribbon-spool, the combination of a 110 core having a recess, a swinging clasp adapted to carry the ribbon thereinto, an impaling point or points adapted to hold the ribbon in said recess, and means on said clasp for embracing said core and holding said clasp in 115 working position.

Signed at the borough of Manhattan, city of New York, in the county of New York and State of New York, this 7th day of March, A. D. 1901.

CHARLES H. SHEPARD.
